UNITED STATES PATENT OFFICE

172,418

FLASHLIGHT HOLDER

Arthur H. Crapsey, Jr., Rochester, N. Y., assignor to Eastman Kodak Company, Rochester, N. Y., a corporation of New Jersey

Application February 19, 1954, Serial No. 29,126

Term of patent 14 years

(Cl. D48—24)

To all whom it may concern:

Be it known that I, Arthur H. Crapsey, Jr., a citizen of the United States of America, residing in Rochester, in the county of Monroe and State of New York, have invented a new, original, and ornamental Design for Flashlight Holder, of which the following is a specification, reference being had to the accompanying drawings, forming a part thereof, in which:

Fig. 1 is a rear perspective view of a flashlight holder, showing my new design; and

Fig. 2 is a front perspective view thereof.

I claim:

The ornamental design for a flashlight holder, as shown.
